UNITED STATES PATENT OFFICE.

HERMAN IHLENBURG, OF PHILADELPHIA, PENNSYLVANIA, ASSIGNOR TO DAVID WOLFE BRUCE, OF NEW YORK, N. Y.

DESIGN FOR TYPE.

SPECIFICATION forming part of Design No. 15,752, dated January 27, 1885.

Application filed December 13, 1884. Term of patent 14 years.

To all whom it may concern:

Be it known that I, HERMAN IHLENBURG, (assignor to DAVID WOLFE BRUCE,) of the city and county of Philadelphia, Pennsylvania, have invented and produced a new Design for a Font of Printing-Type, of which the following is a specification.

The nature of my design is clearly shown in the accompanying typographic impression, to which reference is made; and it consists of a letter of the class known as "modern antique," shaded upon the left by a series of short light horizontal lines, as shown.

The character of the design is preserved in the punctuation-marks, the numerals, and the ¹⁵ dollar and pound-sterling symbols.

Having described my invention, I claim—

The design for a font of printing-type, substantially as shown and described.

HERMAN IHLENBURG.

In presence of—

SAMUEL T. TAUSK,
JOHN MILLER.
